Inventor:
James G. Dudley,
by George Francis Myers,
Attorney.

UNITED STATES PATENT OFFICE

JAMES G. DUDLEY, OF NEW YORK, N. Y.

WINDOW

Application filed September 27, 1930. Serial No. 484,734.

My invention relates to non-fixed or ventilating windows, and has for its object an improvement in construction whereby the setting of the glass in the weather face of the window, the painting of the weather face, and the cleaning of the weather face, may one or all be wholly done entirely from the inside of the room in which the window is installed.

10 A further object is to secure the foregoing results with the utmost simplicity of fabrication and after-manipulation when in use and with the minimum of added cost over other window constructions not embodying these results.

Another object is to construct a glass carrying frame within and hinged to swing from any usual frame which is movable at will to secure ventilation.

20 Other objects and advantages of the present invention will be apparent from the following description, reference being had to the accompanying drawing wherein the preferred form of embodiment of the invention is clearly shown, and wherein similar numerals of reference denote similar parts throughout the several views.

Referring now to the said drawing:

Figure 1 is a horizontal sectional view 30 looking downward, of an outswinging metallic casement window in a room.

Fig. 2 is an enlarged fragmentary sectional view at one of the window jambs.

The invention is constructed and operated substantially and preferably as follows:

1 is the wall jamb, and 2 the window sill. Anchored to the wall jambs by means of 3 is the wall or ventilating frame, or window carrying frame 4, acting as stop beads for the outswinging ventilating frame 5. This frame 5 is pivoted to the wall frame 4 by means of the hinge 6, and carries within its interior peripheral construction the inward-swinging glass carrying frame 7 hinged as at 8; 11 being the glass portion thereof, 12 being the glazing cement and 13 being a metal block.

When closed the herein described window has the wall frame 4, the outswinging ventilating frame 5, and the inswinging glass

frame 7 and glass 11 co-functioning to form a continuous plane sealed against wind and water penetration due to the intimate metal to metal contact of the several frames one against the other.

55 When the window is to be opened to secure ventilation the ventilating frame 5 carrying the glass frame 7 is released from a latch as 9 anchored to the wall frame 4, and is then swung outward thereby carrying with it (as if integrally incorporated therewith) the glass frame 7 which is latched thereto by any suitable means as 10.

When the window needs cleaning, repainting or repairing of its weather face then the 65 ventilating frame 5, in a closed and latched position, or in an unlatched and outswung position, as shown in Fig. 1, the glass frame 7 is unlatched from said ventilating frame by turning latch 10 and is swung inward into 70 easy access for handling wholly inside the room. When the necessary manipulation is completed the glass frame 7 is again latched to the ventilating frame 5 as in its original state.

75 As my invention is in some of its aspects generic, I do not limit myself to the particular construction shown and described, but also contemplate the employment of such equivalents as fairly fall within the scope of the 80 claims.

In this connection I may state that the invention is capable of application to many types of ventilating windows other than outswung casement windows, and may be constructed of metal or wood or the like. While the main swinging frame is shown swung outward, and the glass carrying frame is swung inward, these directions may be reversed, or changed as desired.

90 Therefore it should be understood that I may make various changes in the form, proportion, size and detail of the structure shown and described, and the number and position of certain elements used, without departing 95 from the spirit of the invention.

I claim:

1. A ventilating window, comprising an angular frame having one leg thereof anchored to the wall opening and a second leg 100

normal to the plane of the wall opening forming a weather tight seating for an angular ventilating frame with one leg seating on the free leg of the wall frame and one leg bent 5 away from the planes of the wall opening, hinging means anchored to the wall frame and to the ventilating frame permitting the swinging of the ventilating frame relative to the wall frame, an angular glass carrying 10 frame having one leg bent away from the planes of the wall opening to an identical angle with the bent leg of the ventilating frame thereby forming a weather tight seating for the glass carrying frame with its second leg disposed in the same plane as that of the unbent leg of the ventilating frame, hinged means anchored to the ventilating 15 frame and to the glass carrying frame per-

mitting the swinging of the glass carrying frame relative to the ventilating frame, means for latching the ventilating frame to the wall frame, and means for latching the glass carrying frame to the ventilating 70 frame.

2. A metal ventilating window in a wall opening, comprising a ventilating frame composed of angles with bent legs, and an angular glass carrying frame having one leg bent 75 away from the plane of the wall opening to an identical angle with the bent leg of the ventilating frame thereby forming a weather tight seating for the glass carrying frame with its second leg disposed in the same plane 80 as that of the unbent leg of the ventilating frame.

JAMES G. DUDLEY.
